United States Patent

Des. 238,024
Patented Dec. 16, 1975

238,024

SEAT

Stanley P. Nash, Rte. 1, Riverhill Drive,
Johnson Creek, Wis. 53038

Filed Feb. 11, 1974, Ser. No. 441,164

Term of patent 7 years

Int. Cl. D6—01

U.S. Cl. D6—63

FIG. 3

FIG. 4

FIG. 1 is a front perspective view of my design in the form of a sofa;

FIG. 2 is a view in rear elevation thereof;

FIG. 3 is a front perspective view of the seat of FIG. 1 in the form of a settee; and

FIG. 4 is a front perspective view of the seat of FIG. 1 in the form of an armchair.

The side of the seat not shown is a mirror image of the side shown.

I claim:

The ornamental design for a seat, as shown and described.
